UNITED STATES PATENT OFFICE.

LEVI A. STOKES, OF POINT RICHMOND, CALIFORNIA.

OIL-BURNER.

1,051,464.

Specification of Letters Patent. Patented Jan. 28, 1913.

Application filed June 25, 1912. Serial No. 705,894.

To all whom it may concern:

Be it known that I, Levi A. Stokes, a citizen of the United States, residing at Point Richmond, in the county of Contra Costa and State of California, have invented a new and useful Oil-Burner, of which the following is a specification.

This invention relates to liquid fuel or hydro-carbon burners, and aims primarily at the production of a burner capable of producing a high degree of combustion of the fuel in order to produce a maximum heating effect with a minimum fuel supply.

The present invention also contemplates a burner wherein the fuel is atomized and sprayed by a fluid under pressure, such as steam, in order that the atomized fuel will commingle with the steam to provide a highly combustible vapor.

Among its other objects, the present invention aims to provide a burner of the character indicated, which shall be adjustable to suit the various conditions to which it may be subjected; which is simple, durable, substantial and inexpensive in construction; which will provide a compact injector burner for producing a fan-like flame; which embodies a vapor chamber for receiving the vapor and from which the vapor is discharged to provide the flame; and which shall be convenient, serviceable and efficient in its use.

With the foregoing general objects outlined, and other objects in view, which will be apparent as the invention is better understood, this invention resides in the novel construction and combination of parts hereinafter set forth and claimed, it being understood that this device is susceptible of alterations or deviations in its details within the scope of the appended claims without departing from the spirit of the invention.

The invention has been illustrated in its preferred embodiment in the accompanying drawings, wherein,

Figure 1 is a plan view of the burner. Fig. 2 is a longitudinal vertical section thereof, parts being broken away. Figs. 3 and 4 are sectional details taken on the lines 3—3 and 4—4 of Fig. 2, respectively.

Referring specifically to the drawings, the present burner embodies a body or fuel cylinder 5, which is provided with a lateral port 6 intermediate its ends for attachment to a suitable fuel-supply pipe leading to a source of fuel, such as crude oil or the

like. The outer end of the cylinder 5 is provided with an internal rabbet 7, and a vapor chamber 8 of rectangular cross section is attached to the outer end of the fuel cylinder 5, the vapor chamber 8 having an extension 9 at its inner end screw-threaded into the rabbet 7 and having a shoulder 10 abutting or seating against the other end of the cylinder. The outer end of the vapor chamber 8 is convex or semi-circular and is provided with one or more slots 12, in this case one, extending along the direction of curvature.

The diameter of the bore passing through the extension 9 of the vapor chamber 8 is less than the internal diameter of the cylinder 5, and a mixing tube 14 is screw-threaded through the extension 9 and has a head 13 fitting slidably in the cylinder 5 and abutting against the said extension 9. The mixing tube 14 has a reduced tip 15 projecting into the inner end of the vapor chamber 8, and the head 13 is provided with a conical bore 16 leading to the bore 17 of the mixing tube which extends through the tip 15.

At its inner or rear end, the cylinder 5 is provided with an internal flange 28, and a bushing 18 is screw-threaded through the flange 28, the said bushing having an external flange 19 at its outer end seating against the outer face of the flange 28. A steam nozzle 20 is screw-threaded through the bushing 18 and has a tapered portion 21 and a reduced tip 22 entering the head 13 and mixing tube 14, respectively. The taper of the portion 21 is less than the taper of the bore 16 of the head 13 and the external diameter of the tip 22 is slightly less than the diameter of the bore 17, so that a small annular space is provided between the external walls of the tip 22 and the internal walls of the mixing tube 14. The bore 23 of the steam nozzle 20 is decreased in diameter within the tapered portion 21 and the tip 22, as designated by the numeral 24, and the outer end of the reduced portion 24 of the bore is countersunk or beveled, as indicated by the numeral 25. The binding nut 26 is screw-threaded on to the nozzle 20 and is designed to bind against the bushing 18 in order to lock the nozzle at any position to which it is set or adjusted.

The foregoing parts may be constructed from any suitable material, such as metal, and may be made of various sizes and pro-

portions, as will be found necessary or desirable.

In practice, the liquid-fuel supply pipe is attached to the port 6 in order to supply crude oil or other liquid fuel to the fuel chamber 27 within the cylinder 5, and a steam pipe leading to a suitable source of steam, is attached to the inner end of the steam nozzle 20, it being understood that other suitable fluid under pressure could be substituted for steam. Then as the steam is forced forwardly or outwardly of the tip 22 of the steam nozzle, the oil is drawn forwardly around the tip 22 and is atomized and sprayed by the jet of steam, the atomized oil and steam mixing within the tube 14 and tip 15 and then passing into the vapor chamber 8 in the form of a highly combustible vapor. The vapor accumulates in the vapor chamber 8 and is consequently under pressure due to the continuous ingress of vapor from the mixing tube, and the vapor is then discharged through the slot 12 to provide a fan-like flame. This flame being fan-like covers a comparatively large area and distributes the heat accordingly, so as not to concentrate the flame in the manner of a needle flame which, when contacting with an object is most likely to fuse or injure same.

The steam nozzle 20 being screw-threaded to the bushing may be adjusted longitudinally so as to cause the proper atomization of the fuel, according to the density or pressure of the fuel. The fuel may be supplied to the cylinder 5 either under pressure, such as by gravity or by means of a force pump, or the steam may be made to suck the fuel, as will be understood.

It will be noted that with the form of burner set forth, the steam and oil are mixed thoroughly within the vapor chamber 8 prior to discharge therefrom, which provides for a clear bright flame, devoid of black or heavy smoke, indicating a thorough consumption of fuel or a high degree of combustion. This burner requires no baffles or perforated plates for the oil to pass through, the oil flowing directly to the steam nozzle, and the arrangement of steam nozzle and oil chamber, prevents any back pressure on the oil and causes the proper atomization of the oil. It is understood that the slot 12 may be of any suitable size to regulate the discharge of vapor, or that one or more of the said slots may be provided in order to produce a single flame or a plurality of flames lying in parallel planes. Owing to the pressure of the gas collecting in the vapor chamber 8, there is no possibility of the waste of oil.

The burner may be readily assembled and taken apart for purposes of repair, cleaning or replacement, and it will be noted that the mixing tube may be readily disengaged

from the vapor chamber 8 in order to provide ready access into the vapor chamber for the purpose of cleansing same. This burner may be employed as an injector burner for steam boilers and the like, or may be employed in heating furnaces, stoves, and in fact for a multitude of purposes, as will be apparent to those skilled in the art. As a whole, the present burner provides a desirable one for the purposes for which it is designed.

Having thus described the invention, what is claimed as new is:—

1. A fuel burner embodying a fuel cylinder, a vapor chamber engaged to the outer end thereof, a mixing tube engaged through the inner end of the vapor chamber and having a head fitting in the cylinder, and a steam nozzle adjustable through the cylinder and having a tip entering the mixing tube.

2. A fuel burner embodying a fuel cylinder having a lateral port, a vapor chamber attached to the outer end of the cylinder and having a discharge outlet, a mixing tube between the cylinder and vapor chamber, and a steam nozzle adjustable through the inner end of the cylinder with its tip projecting into the mixing tube.

3. A fuel burner embodying a fuel cylinder having a lateral port, a vapor chamber screw-threaded into the outer end of the cylinder, a mixing tube screw-threaded into the inner end of the vapor chamber and having a portion fitting in the cylinder, and a tip projecting into the vapor chamber, and a steam nozzle screw-threaded through the inner end of the cylinder with its tip entering the mixing tube.

4. A fuel burner embodying a fuel cylinder having a lateral port, a vapor chamber having an inner reduced extension screw-threaded into the outer end of the cylinder, a mixing tube screw-threaded through the said reduced extension and having a head fitting in the cylinder, and a tip projecting into the vapor chamber, and a steam nozzle screw-threaded through the inner end of the cylinder and having a reduced tip entering the mixing tube.

5. A fuel burner embodying a fuel cylinder having an internal rabbet and internal flange at its outer and inner ends, respectively, a vapor chamber of rectangular cross section having a screw-threaded extension engaging in the said rabbet and having a shoulder seating against the outer end of the cylinder, the vapor chamber having its outer end convex and provided with a slot, a mixing tube screw-threaded through the said extension and having a head fitting in the cylinder and abutting against the said extension, the mixing tube having its tip projecting into the vapor chamber and the head having a conical bore leading to the

bore of the mixing tube, a bushing screw-threaded into the flange of the cylinder, and a steam nozzle screw-threaded through the bushing and having a tapered portion and a reduced tip entering the said head and mixing tube, respectively.

6. A fuel burner embodying a fuel cylinder, a vapor chamber engaged to the outer end of the cylinder, a mixing tube engaged through the inner end of the vapor chamber and having a head fitting in the cylinder, the mixing tube having its tip projecting into the vapor chamber and the head hav-

ing a conical bore leading to the bore of the mixing tube, and a steam nozzle adjustable through the inner end of the cylinder and having a tapered portion and a reduced tip entering the said head and mixing tube, respectively. 15

In testimony that I claim the foregoing 20 as my own, I have hereto affixed my signature in the presence of two witnesses.

LEVI A. STOKES.
